UNITED STATES PATENT OFFICE

102,056

DESIGN FOR A COMBINED FAN BLADE AND SHAFT GUARD

Andrew S. Knapp, St. Louis, Mo., assignor to
Knapp-Monarch Company, St. Louis, Mo., a
corporation of Missouri

Application June 26, 1936, Serial No. 63,503

Term of patent 7 years

To all whom it may concern:

Be it known that I, Andrew S. Knapp, a citizen of the United States and a resident of the city of St. Louis and State of Missouri, have invented a certain new, original, and ornamental Design for a Combined Fan Blade and Shaft Guard, of which the following is a specification, reference being had to the accompanying drawing, forming part thereof.

Figure 1 is a front elevational view of a

combined fan blade and shaft guard showing my new design.

Figure 2 is a plan view thereof; and

Figure 3 is a slightly enlarged sectional view on the line 3—3 of Figure 2.

I claim:

The ornamental design for a combined fan blade and shaft guard, as shown.

ANDREW S. KNAPP.
